FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

STRIPING ATTACHMENT FOR CIRCULAR KNITTING-MACHINES.

1,357,253.

Specification of Letters Patent.

Patented Nov. 2, 1920.

Application filed April 10, 1919. Serial No. 289,009.

To all whom it may concern:

Be it known that I, FRANK W. ROBINSON, a citizen of the United States, residing at the city of Reading, in the county of Berks 5 and State of Pennsylvania, have invented certain new and useful Improvements in Striping Attachments for Circular Knitting-Machines, of which the following is a specification.

10 My invention relates to circular knitting machines and particularly to improvements in vertical striping mechanism therefor fully set forth in connection with the accompanying drawing and defined in the subjoined 15 claims.

Figure 1 is an elevation showing my improved attachment in connection with adjacent parts of circular knitting machines.

Fig. 2 is an elevation taken at right angles 20 to Fig. 1.

Fig. 3 is a plan view with portions broken away to show a section on the line 3—3 of Fig. 1.

Figs. 4, 5 and 6, 7 are vertical views of the 25 finger-stop cams employed respectively at the outer sides of and between the closely arranged pair of swinging fingers shown.

The drawing indicates the usual circle of knitting needles 3, and a latch ring 4, having 30 guide openings 5 and 6 for guiding the knitting thread and high-splice thread commonly employed; in connection with a suspension plate 10 for the striping-thread carrier fingers 11 to which the striping threads 35 12 are fed. This suspension plate 10, which is supported in a suitable manner, and is provided with a socket bearing 22 for each of the swingingly mounted striping-thread fingers employed, substantially as shown in

40 my prior Patent No. 1,203,131 issued Oct. 31, 1916, to which reference is made as a setting forth of the general construction to which my present improvements relate; the needle-engaging swing of each finger being

45 imparted by a contacting cam or cams 30, 30^a arranged in the path of rollers 27 at the end of a rigid laterally extending operating arm 25 of each finger, and with rollers 28 at the ends of right-angular head plates 26, 50 rigidly secured to said arms 25, so as, in cooperation with finger-retracting springs 29, to successively swing the thread carried by each finger, first between determined needles, then across the needle or needles to be en-

gaged by such thread, and finally back to 55 starting position.

In my present construction shown these striping-thread carrier fingers are arranged in diametrically opposite pairs, so as to knit in closely parallel vertical stripes on each 60 side of a stocking; and to provide for making each finger engage a plurality of striping threads upon determined needles at each swing of the finger, as may be desired, I form it with a forked end having parallel 65 thread-guide prongs 35, 35 which are spread to correspond with the needle spacings and adapted to simultaneously carry separate striping threads between different needles. The particular needles between which the 70 striping threads are to be swung, and upon which they are to be engaged by lateral movement of the fingers, calls for very nice regulation of the finger swings in order that each finger may be made to reliably produce 75 a determined uniform stripe. And in order that this striping may be satisfactorily continued in connection with the usual high-splicing operation referred to, provision is required for taking care of the so-called 80 floating threads extending between the end needles of the high-splicing series, as indicated at 8 Fig. 3.

For regulating the needle-engaging swing of the striping-thread fingers 11, I employ 85 a pair of independently adjustable finger-stop cams 36, 37, for each finger; which cams are secured in adjusted positions to rigid supports 38, 38 depending from the suspension plate 10 as shown, by means of screw-threaded shank portions 40 engaged in apertures in the supports 38 and provided with lock nuts 41.

A pair of these stop cams is arranged on opposite sides of each striping-thread finger 11, so as to limit the needle-engaging swing of the latter in each direction as determined by their independent adjustment; their points of contact with the finger being so near to the free ends of the latter as to 100 facilitate the accurate setting required. To permit the use of separate cam stops between the closely arranged striping-thread fingers as shown, the eccentric body portions of these are flattened, and the stops are 105 mounted one above the other as indicated. The rollers 27—28 are of different lengths so as to permit of separate or joint operation

of the fingers by separate cams 30, 30^a, or a single adjustable cam if desired, as indicated.

To provide for preventing the floating 5 high-splice threads 8 from coming in contact with the ends of the striping-thread fingers 11 or the threads carried thereby, I provide a deflecting device 40 for said floating threads 8, which device is fastened to 10 the rigid supports 38 for the finger-stop cams, and depends within the needle cylinder so as to hold the floating threads away from the striping fingers as indicated, the dotted lines 51 showing how the floating 15 thread would engage the fingers 11, if not thus supported, and interfere with the free operation thereof.

As each striping thread finger 11 is independently adjustable to vary the needle-engaging swing imparted to it, the width of 20 each stripe may be accurately determined as desired, the number of striping threads carried by each forked finger may be varied to change the character of the stripe produced; 25 and the fingers may be operated to produce broken stripes as desired by intermittent adjustment of the cams 30, 30^a to operative

or inoperative positions. In all cases the striping may be continued without interference by the floating high-splice threads. 30

What I claim is:—

1. A vertical striping attachment for circular knitting machines comprising independently suspended adjacent thread-carrier fingers, means for imparting intermittent needle-engaging swings to the thread-guide ends of said fingers, and separate pairs of independently pivoted needle-stop cams operative upon the respective fingers to variably limit their swings, one cam of each 40 pair being located between adjacent fingers.

2. In a circular knitting machine comprising feed mechanism for a main knitting thread and for a high-splicing thread; oppositely arranged striping-thread carrier 45 fingers and means for imparting intermittent needle-engaging swings to the thread-guide ends thereof, and a deflecting device for the floating high-spliced threads depending within the needle cylinder and arranged 50 to prevent interference of said threads with the striping operation.

In testimony whereof I affix my signature.

FRANK W. ROBINSON.
